(57) **CLAIM**

I claim, the ornamental design for vehicle, as shown and described.

DESCRIPTION

FIG. 1 is a front perspective view of a vehicle, showing my new design;

FIG. 2 is a front elevation view thereof;

FIG. 3 is a rear elevation view thereof;

FIG. 4 is a side elevation view thereof taken from the left of FIG. 2;

FIG. 5 is a side elevation view thereof taken from the right of FIG. 2; and,

FIG. 6 is a top plan view thereof.

The broken lines depict portions of the vehicle that form no part of the claimed design.
